WOOD TURNING DEVICE

Gustav Burgeson, Youngstown, Ohio

Application August 3, 1944, Serial No. 547,904

2 Claims. (Cl. 142—38)

This invention relates to a wood turning device and more particularly to templates and rasps for wood turning.

The principal object of the invention is the provision of apparatus adapted to be used in wood turning.

A further object of the invention is the provision of means for adjustably positioning a pair of templates adjacent a section of wood to be turned.

A still further object of the invention is the provision of a wood turning apparatus taking the form of a pair of templates so positioned as to form guides for rasps used in wood shaping.

A still further object of the invention is the provision of means for forming templates to be employed in connection with the template mounting means.

A still further object of the invention is the provision of a plurality of various shaped wood rasps adapted for use with the templates and template mounting means of the wood turning device.

The templates and rasps for wood turning shown and described herein have been designed to provide a simple and efficient apparatus for home work shop use in turning wood in various ornamental shapes commonly employed in furniture construction and the like. The templates and rasps and their mounting means which enable them to be used in the wood turning operation are simply formed and, therefore, capable of economic manufacture and hence wide distribution. The formation of the templates and their mounting means facilitate the individual design and formation of templates incorporating various original designs on the part of the user of the wood turning device.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a perspective elevation of a wood turning device.

Figure 2 is a perspective elevation of a portion of the device illustrated in Figure 1.

Figure 3 is a cross sectional elevation of a template pattern as used with the device illustrated in Figure 1.

Figure 4 is a plan view of a double handled wood rasp.

Figure 5 is a cross sectional elevation of a wood rasp such as illustrated in Figure 4.

Figure 6 is a cross sectional elevation of a modification of the wood rasp illustrated in Figure 5.

Figure 7 is a cross sectional elevation of a modification of the wood rasp such as illustrated in Figure 5.

By referring to the drawing and Figure 1 in particular will will be seen that the wood turning device illustrated consists of a base 10 having a pair of brackets 11 and 12, respectively, positioned adjacent its opposite ends, the said brackets 11 and 12 forming journals 13 and 14 located on an axially extending center line of the base 10, and at a suitable distance thereabove. Lathe-like members 15 and 16, respectively, positioned in the journals 13 and 14 serve to rotatably position a work piece such as indicated by the numeral 17. It is obvious that suitable rotating motion imparted to either one of the rotatable lathe-like members 15 and 16 will cause the work piece 17 to revolve. In order that the work piece 17 may be shaped as by a wood turning operation, means is provided for the mounting of guiding templates adjacent thereto and comprises a pair of U-shaped frames 18 and 19, respectively, which frames 18 and 19 are adapted to be firmly positioned on the base 10 as by means of nut and bolt assemblies 20 engaging openings 21 in the U-shaped frames 18 and 19 and positioned through a longitudinally extending slot 22 in the base 10.

By referring to Figure 2 it will be seen that each of the U-shaped frames 18 and 19 is provided on the inward sides of its upwardly extending arms with a pair of secondary brackets 23 and 24, respectively, which are mounted thereon in an adjustable manner by means of nut and bolt assemblies 25 which pass through openings 26 in the secondary brackets 23 and 24 and through slots 27 in the upwardly extending arms of the U-shaped frames 18 and 19, it being observed that each of the upwardly extending arms of the frames 18 and 19 are provided with a slot 27 so that the secondary brackets 23 and 24 may be adjustably positioned thereon and form in effect a portion of the upwardly extending arms of the frames 18 and 19. This construction forms a mounting means for a pair of templates 28 and 29, as illustrated in Figure 1, and provides for the rigid positioning of the templates 28 and 29 in appropriate positions at each side of the work piece 17 with the bases of the templates 28 and 29 on a transversely positioned center line with

respect to the axis of the work piece 17. In order to shape the work piece 17 in accordance with the predetermined design of the templates 28 and 29 which serve as guides and support means for the actual wood shaping tools, a wood rasp 30 provided with a pair of handles 31 and 32, respectively, is used and is adapted to be positioned across the top of the templates in transverse relationship to the work piece 17 and to the templates 28 and 29 so that the roughened surface of the rasp 30 engages the work piece 17 and is capable of cutting away the material of the work piece 17 so as to slowly move it along the templates 28 and 29 thereby passing the work piece in accordance with the predetermined pattern of the templates.

It will thus be seen that a simple and yet efficient means of wood turning has been disclosed whereby various ornamental wood turnings may be easily produced by an amateur as, for example, in home work shops.

By referring now to Figure 3 of the drawing a pair of templates such as those illustrated at 28 and 29 in Figure 1 may be seen in the process of formation whereby two sections of plywood or other suitable material, as indicated by the numerals 28 and 29, have been formed from a pattern so as to provide a desirable configuration as indicated at 33 and the two pieces 28 and 29 then placed back to back as illustrated to show the configuration of a wood turning formed in accordance therewith. It is obvious that these two templates 28 and 29 are placed in the U-shaped brackets 18 and 19, illustrated in Figure 1, in a clamp therein as by means of nut and bolt assemblies 25 so that the configuration 33 thereof may be imparted by means of the rasp 30 to the work piece 17.

By referring now to Figure 4 a plan elevation of a wood rasp may be seen wherein the wood cutting section thereof is indicated by the numeral 30 and the rasp provided with a pair of handles 31 and 32. It will be obvious that the wood cutting section 30 is preferably formed to terminate short of the ends of the rasp so as to

provide for the smooth engagement of the rasp body with the configurations of the templates with which it is adapted to be used.

In Figures 5, 6 and 7 cross sectional elevations 30A, 30B and 30C indicate desirable alternate cross sectional forms of the rasp 30, illustrated in Figures 1 and 4, to enable various configurations to be imparted to the work piece being turned.

It will thus be seen that a simple and efficient wood turning device has been disclosed wherein a relatively inexpensive construction serves to enable a work piece to be turned through the use of appropriately formed rasps in a practical and satisfactory manner.

Having thus described my invention, what I claim is:

1. In a wood turning device, a base including a pair of brackets for rotatably supporting a work piece therebetween, a slot formed in said base, a pair of templates on opposite sides of and means for mounting the said templates adjacent the said work piece, said mounting means comprising a pair of U-shaped brackets positioned on said base and secured thereto by means of fasteners engaging the said slot, the said brackets including means for clamping the said templates in position thereon, together with a rasp adapted to be positioned transversely with the said templates and work piece so that the work piece may be shaped thereby.

2. In a wood turning device including a lathe-like base for rotatably mounting a work piece, a slot formed in said base and a pair of U-shaped brackets positioned on the said base and secured thereto by means of fasteners engaging the said slot, secondary brackets affixed to the said U-shaped brackets for mounting templates thereon, the said templates being parallel with respect to the said rotatable work piece and located one at each side thereof together with a rasp for transverse positioning across the said templates and work piece so that the work piece may be shaped thereby.

GUSTAV BURGESON.
